HARRY BRETTLER, OF BROOKLYN, NEW YORK, ASSIGNOR TO IDEAL LIGHTING NOVELTY CO., OF NEW YORK, N. Y., A PARTNERSHIP CONSISTING OF HARRY BRETTLER AND ARON HOLENDER

DESIGN FOR A SHADOW LAMP OR ARTICLE OF ANALOGOUS NATURE

Application filed August 30, 1930. Serial No. 36,835. Term of patent 3½ years.

To all whom it may concern:

Be it known that I, HARRY BRETTLER, a citizen of the United States of America, and a resident of Brooklyn, county of Kings, and State of New York, have invented a new, original, and ornamental Design for Shadow Lamps or Articles of Analogous Nature, of which the following is a specification, reference being had to the accompanying drawing, forming a part hereof.

In the drawings:

Figure 1 is a front elevational view of the

shadow lamp or article of analogous nature, the dominating feature of which is the horse drawn coach in relief in front of the glass; and

Figure 2 is a diagrammatic end view of the shadow lamp or article of analogous nature.

I claim:

The ornamental design for a shadow lamp or article of analogous nature substantially as shown and described.

HARRY BRETTLER.
